CLAIM

The ornamental design for the shoulder pads and plastic bucklet suspender, as shown and described.

DESCRIPTION

FIG. 1 is a perspective view of the shoulder pads and plastic bucklet suspender showing its basic configuration and design;

FIG. 2 is a frontal view of FIG. 1 thereof;

FIG. 3 is an elevational rear view of FIG. 1 thereof;

FIG. 4 is an elevational top view of FIG. 1 thereof;

FIG. 5 is an elevational bottom view of FIG. 1 thereof; and,

FIG. 6 is an elevational side view of FIG. 1, the other side being of mirror image thereof.
